UNITED STATES PATENT OFFICE.

VICTOR A. GEBHARDT, OF CINCINNATI, OHIO.

FINGER-RING AND THE LIKE.

1,280,707.

Specification of Letters Patent. Patented Oct. 8, 1918.

Application filed January 29, 1916. Serial No. 75,051.

To all whom it may concern:

Be it known that I, VICTOR A. GEBHARDT, a citizen of the United States, and a resident of the city of Cincinnati, in the county 5 of Hamilton and State of Ohio, have invented certain new and useful Improvements in Finger-Rings and the like, of which the following is a full, clear, and exact description, reference being had to the 10 accompanying drawing, forming part of this specification.

My invention relates to finger rings and more particularly to rings which are given and received in conformance with custom or 15 ceremony, such as wedding rings for example.

It has hitherto not been a possibility to procure a ring which presented the appearance of a complete ring and which could, 20 however, be gradually embellished with jewels or stones without at any time destroying the appearance of the ring as a complete article.

I am aware that it is old in the art to 25 mount a stone in a piece of jewelry by making a depression in the piece of supporting metal and placing the stone in the depression and securing it in place. But so far as I am aware it has never been suggested that a ring could be provided which 30 was equipped with such depressions for stone mountings, said depressions made entirely around the ring so as to have the appearance of a decoration of the ring as well 35 as providing a place for the insertion of precious stones and the like from time to time without destroying the appearance of the ring.

Thus it is the object of my invention to 40 provide a ring for a wedding ring particularly, which is decorated with a design in the form of depressions, the same being plain or embellished. It is my object that this design be completely cut around the 45 ring so that the whole is relieved from the chance of appearing like a ring which has lost its set.

I am aware that my new ring might be 50 considered as coming under the type of patents known as design patents, but I consider the mechanical feature of the novel ring as predominant in importance over any particular design that might be adopted, since the principal point of the invention

is to have a design of ornamental appearance completely around the ring, said design being arranged so that there are a series of depression that will receive, if desired, souvenir jewels or the like, and said depressions being spaced equally apart so 60 as to relieve the ring from an unfinished appearance at any time before or during its embellishment with souvenir stones.

It is thus possible with the ring which I contemplate for a wedding or other anniversary ring to start the custom of the giving by the donor to the recipient of an additional precious stone as a setting for the ring at each succeeding anniversary.

In the drawing which illustrates an embodiment of my invention,

Figure 1 is a perspective view of the ring.

Fig. 2 is a cross section thereof.

Fig. 3 is a front elevation thereof.

The ring has an annular body 1 in which 75 are cut, or formed as desired, a series of depressions or indicating marks 2. These depressions or indicating marks are equally spaced around the entire body of the ring as I have found this to be necessary, to 80 preserve the proper appearance for the ring.

In forming the indicating marks they may, of course, be worked into a scroll design or the like, and the indicating marks may be engraved with some design. In the 85 device as shown there are no efforts at design because in the preferred form the depressions, provided they are carefully and uniformly cut, will provide a graceful and dignified design that is all that is desired 90 in such a ring. The depressions are preferably cup shaped, although some slightly modified shape could be used so as to appeal to the preference of various buyers, or the indicating marks could merely assume 95 the character of indicating marks to indicate where the additional jewels are to be mounted with each succeeding anniversary.

As a preferable construction, the ring is intended to serve as a wedding ring and it 100 will therefore take the form of the regulation gold band ring, with a single stone mounting for the first year, or in the start the ring need not be provided with any stone, but serve as the simple gold wedding 105 ring.

The object is to provide a ring which shall always have the appearance of a fin-

ished ring, and not as a ring which has lost one or more of its settings, but which shall also indicate to the donor and to the wearer that each succeeding anniversary should be 5 commemorated by an additional stone.

I do not wish to be limited in the claim that follows because of a failure to fully appreciate the full application of my invention as expressed therein, or because of a failure 10 to mention other modifications of my invention which would naturally suggest themselves to a jeweler, in meeting some special conditions in his art.

Having thus described my invention, what

I claim as new and desire to secure by Letters Patent, is:—

A finger ring to serve as a souvenir ring, comprising an annular band of precious metal having spaced around its periphery a series of jewel receiving portions, said portions being set closely adjacent to each other around said periphery, said portions comprising cup-shaped depressions in the ring in which the jewels may be set from time to time, so that said ring may be used as a souvenir, said depressions without the gems forming a pleasing design around the ring.

VICTOR A. GEBHARDT.
